DEVICE FOR CLEANING MEDICAL
AMPOULES AND THE LIKEHeinrich Strunck and Johann Ruhl,
Köln, Germany

Application August 5, 1950, Serial No. 177,794

Claims priority, application Germany
November 9, 1949

5 Claims. (Cl. 134—152)

1

This invention relates to a device for cleaning medical ampoules or similar small glass vessels.

In prior devices ampoules to be cleaned are put, with their openings turned downward, into a container filled partly with a cleaning liquid. By periodically evacuating the whole container and connecting it with the atmosphere the cleaning liquid is caused to enter into the ampoules and flow back when the container is evacuated. These prior devices do not reliably clean the whole interior of the ampoules, especially the bottoms thereof.

It is an object of the present invention to provide an improved apparatus for cleaning ampoules so as to free them of all impurities and to dry and sterilize them in several consecutive treatment steps. Another object is to simplify and reduce the costs of cleaning ampoules.

In accordance with the present invention, a number of ampoules are put with their mouths turned downward into a downwardly movable ampoule holder. When the ampoule holder is moved downward the mouths of the ampoules are disposed by guide funnels so that stationary hollow needles can be introduced into the ampoules through which needles cleaning agents are forced into the ampoules, said agents flowing off again along the shafts of the needles. These needles may be stationary and the ampoule holder together with the ampoules and guide funnels may be lowered so as to cause the hollow needles to enter into the ampoules. The introduction of the needles presents no difficulties and there is no danger that the needles will strike the free edges of the ampoule mouths because the mouths of the ampoules are placed in proper positions by means of the guide funnels. Once the needles are introduced into the downwardly disposed necks of the ampoules, the cleaning may be done more or less intensively. To give an example, fresh water is first injected through the needles. It rushes to the bottoms of the ampoules, flows down again along the ampoule walls and after a violent turbulent action comes out again along the walls of the hollow needles through the ampoule necks. By introducing air under pressure the discharge may be accelerated. Thereupon, a second cleaning and rinsing may be carried out by using a hot lye, followed by another rinsing with fresh water and if desired with distilled water. To eliminate the last traces of liquid hot air may be blown into the ampoules. Finally, cooled sterile air may be blown in. The ampoules will remain sterile for filling if such filling is done shortly after the cleaning because they will slowly get warmer dur-

2

ing the transport and the cooled sterile air contained therein will expand and thus prevent dusty and non-sterile air from entering thereinto.

The hollow needles are held vertically on a base and the free ends thereof are disposed in bores provided in an intermediate plate. These bores form inverted cone-shaped portions which constitute the previously mentioned guide funnels and cylindrical portions which surround the free ends of the needles. The intermediate plate is slidably arranged on vertical guide posts extending from the base and is kept in desired position by means of springs preferably disposed on the guide posts. Stops may be provided for limiting the position of the intermediate plate.

The ampoule holder is removable for inserting therein the ampoules to be cleaned and for manipulating the ampoules thereafter, and when it is inserted in the cleaning device and moved downward the ampoule necks are received by the inverted cone-shaped portions of the bores in the intermediate plate and guided thereby so that the mouths of the necks lie exactly above the cylindrical portions of the bores in which are disposed the free ends of the needles. The ampoules standing with their lower edges on the inner side of the cone shaped portions of the bores (guide funnels) are in slight pressure engagement therewith due to the resiliently mounted intermediate plate. The plate is therewith forced downward and the ampoule holder with its ampoules follows automatically until it meets a stop. The base on which the needles are held is, however, stationary, and the free ends of the needles therefore move into the ampoules. When the ampoule holder meets said stops, the intermediate plate will be forced somewhat downward until the ampoules are free of engagement with the guide funnels. The intermediate plate is kept in its lowermost position by means of a safety device preferably operating automatically. Thereupon, there is put on a lid which may be guided by the guide posts. This lid is preferably provided with openings above the ampoules. The edges of this lid may be bent upward to form a bowl-like structure.

The cleaning agent forced in under pressure through the hollow needles rushes against the bottom of the ampoules, which are thereby somewhat lifted toward the lid. The cleaning agent flows off again along the needles through the ampoule neck. When the pressure is relaxed the ampoules will drop down again without danger of damage to the fragile edges of their necks.

The ampoule holder is preferably provided with

supporting feet, which reach down farther than the ampoule necks, but must not touch the intermediate plate when the holder is inserted into the device. The ampoule holder may comprise two metallic sheets provided with holes. These sheets are connected with each other by guide means and if desired by parts provided with handles. The two iron sheets support the ampoules when inserted in such a way that the shoulder-like parts of the ampoules rest in narrow openings of the lower sheet, and that their bodies are supported laterally by the wider openings of the upper sheet.

The invention will appear more clearly from the following detailed description when taken in connection with the accompanying drawings showing by way of example, a preferred embodiment of the invention and some further advantageous details thereof.

Figures 1 and 2 are vertical sections of a device according to this invention adapted to be inserted in a known rinsing machine; Figure 1 shows the apparatus in the initial position of its parts; Figure 2 shows the apparatus in the final position of its parts just before rinsing is started.

On the revolving table of a rinsing machine, which is not shown as it is well known in the art, there are arranged one or several stationary bottom members. In the drawing such a bottom member is indicated by the reference numeral 10. By means of screw nipples 11 hollow needles 12 are held vertically on the bottom member 10. Under the needle bottom 10, there is a rinsing box 13. A cleaning agent injected into said box under pressure will come out through the free ends of the hollow needles 12. On the needle bottom 10 are disposed two vertical guide posts 14. The intermediate plate 15 is slidable on the posts 14. In this plate 15 there are provided bores, one bore for each needle 12, each bore having a cylindrical portion 16 and an inverted cone-shaped portion 17, both portions constituting a funnel. The plate 15 is normally kept so high above the needle bottom 10 that the free ends of the needles 12 are within the cylindrical portions 16. The plate 15 is pressed upwards by means of springs 18 against stops not shown in the drawing.

The ampoules to be cleaned are inserted, with their mouths turned downwards, into the ampoule holder 20 while the holder is removed from the device. This ampoule holder comprises two metallic sheets 21 and 22 connected with each other by means of spacing parts 23. These spacing parts have tubular guide pieces 24 for sliding engagement with the guide posts 14. The guide pieces 24 are provided with handle buttons 25 to facilitate the handling and transport of the ampoule holder 20. The ampoule holder 20 is also provided with supporting feet 26 shown in the drawing by dotted lines so as to support it when removed from the device. The ampoules 19 are supported with their shoulders resting in openings of the lower plate 21. The approximately vertical position of the ampoules is obtained by their bodies being laterally supported in openings of the upper plate 22 which are of larger diameter.

Another element of the cleaning device is the lid 27 provided with small openings 28 one over each ampoule. The edge 29 of the lid is bent upward. On either side, the lid is fitted with a tubular guide 30 terminating in a handle button 30a.

Ampoules to be cleaned are first placed in the ampoule holder and the latter is inserted into the cleaning device, its tubular guide members 24 sliding over the guide posts 14. The ampoule holder 20 will then be lowered so that its guide members 24 reach the tubular sliding members of the plate 15. The ampoule necks enter into the inverted cone-shaped guide funnel portions 17 and are adjusted exactly in accordance with the cylindrical portions 16. The plate 15 held by its handles 15a is pressed downward against the tension of the springs 18; the ampoule holder 20 follows the free ends of the stationary hollow needles which enter into the ampoules 19. The downward movement of the ampoule holder 20 is stopped when the screws 23a (provided in the tubular members 24) reach the ends of grooves 14a formed in the guide posts 14. The plate 15 is then slightly lowered further until a safety device 31 provided in the sliding tubular members of the plate interlocks automatically with a notch 32 of the guide post 14. In this position of the plate 15 the necks of the ampoules are free of engagement with the cone-shaped guide funnels as may be seen from Figure 2. What remains to be done is to place in position the lid 27 which does not touch the bottoms of the ampoules 19.

The ampoules are cleaned by injecting thereinto, through the needles 12, fresh water and other cleaning liquids and finally, distilled water. The liquid flows out along the needle shafts after thoroughly rinsing the interior of the ampoules. As a result of the pressure brought to bear by the injected liquids, the ampoules 19 are somewhat lifted until their bottoms touch the lid 27. After such cleaning by means of liquids, compressed air, preferably hot, will be blown in with a view to entirely expelling the liquid and to drying the interior of the ampoules. Finally, air cooled to a certain degree and preferably sterilized may be blown in. Cold air may instead be blown on the outside of the ampoules.

The exterior of the ampoules may be cleaned at the same time. This may be done simply by spraying a cleaning liquid upon the bowl-shaped lid 27. The liquid then flows through the openings 28 over the ampoules 19. When the cleaning is done the liquid attaching to the outside is removed by hot air.

The ampoules thus cleaned will now be removed from the apparatus together with the ampoule holder 20 to be taken to a filling machine. The ampoules may remain in the holder 20 while they are filled and closed.

Usually, the bottle rinsing machines of a known type are so designed that, with the progressive rotation of the table, the supply of water, washing lyes, compressed air and the like in their proper order is regulated automatically. When using such a machine for the purpose of the present invention, an ampoule holder 20 with a set of ampoules 19 may be removed after one full rotation of the table, and a new filled ampoule holder may then be inserted.

What we claim is:

1. Device for simultaneously cleaning a number of medical ampoules or the like small glass vessels comprising a base, posts secured to said base, hollow needles disposed on said base and extending vertically therefrom, means forming a rinsing box disposed underneath said base and mounted on said base posts, a plate movably disposed on said posts and having a plurality of funnel-shaped bores, one for each of said needles and each bore in axial alignment with its asso-

ciated needle, each bore having an inverted conical top portion and a cylindrical bottom portion, said plate adapted to be normally biased in a raised position with the upper end of the needles extending within the plate and in its lowered position the needles extending through the plate, spring means on said posts for normally disposing the free ends of said hollow needles in inoperative position in the cylindrical portions of said funnel-shaped bores, means for moving said plate downwardly against the pressure of said spring means to position the free ends of said needles above said plate, an ampoule holder supporting ampoules with their mouths turned downward, said ampoule holder being mounted on said posts for downward sliding displacement thereon to cause the ampoule mouths to enter into the cone-shaped parts of said funnel-shaped bores of said plate and in axial alignment with the cylindrical portions of said bores, said ampoule holder comprises two metallic sheets, spacing members for connecting said sheets one above the other, the lower sheet having openings in which the shoulders of ampoules to be cleaned are resting, the upper sheet having openings of greater diameter in which said ampoules are supported in laterally spaced relationship, guide members connected to said spacing members for sliding engagement with said posts, and stop screws provided in said guide members and guided in grooves provided in said posts, the end of said grooves limiting the downward movement of said ampoule holder.

2. Device for simultaneously cleaning a number of medical ampoules or the like small glass vessels comprising a base, posts secured to said base, hollow needles disposed on said base and extending vertically therefrom, means forming a rinsing box disposed underneath said base and mounted on said base posts, a plate movably disposed on said posts and having a plurality of funnel-shaped bores, one for each of said needles and each bore in axial alignment with its associated needle, each bore having an inverted conical top portion and a cylindrical bottom portion, said plate adapted to be normally biased in a raised position with the upper end of the needles extending within the plate and in its lowered position the needles extending through the plate, spring means on said posts for normally disposing the free ends of said hollow needles in inoperative position in the cylindrical portions of said funnel-shaped bores, means for moving said plate downwardly against the pressure of said spring means to position the free ends of said needles above said plate, an ampoule holder supporting ampoules with their mouths turned downward, said ampoule holder being mounted on said posts for downward sliding displacement thereon to cause the ampoule mouths to enter into the cone-shaped parts of said funnel-shaped bores of said plate and in axial alignment with the cylindrical portions of said bores, a safety device carried by said plate and adapted to interlock with a notch provided in one of said posts, said notch being spaced from said base so that the free ends of the mouths of said ampoules to be cleaned will be free of the walls of the cone-shaped coating portions of said funnel-shaped bores.

3. A device for cleaning medical ampoules comprising a base, a plurality of hollow needles mounted on said base and vertically extending therefrom, a compartment cooperating with said

base for receiving cleaning fluid, posts extending from said base, a plate slidable on said posts, said plate having a bore for each needle which is axially aligned therewith and which has a cylindrical bottom channel and an inverted cone-shaped funnel on top of said channel, spring means for holding said plate in a normal position spaced from said base in which position the free ends of said needles are disposed in the cylindrical channels of their associated bores, a holder slidable on said posts above said plate, and adapted upon being operatively positioned on said plate to follow the movement of said plate, said holder having a plurality of holes for receiving in inverted position ampoules to be cleaned with their mouths directed downwardly each in axial alignment with one of said bores and the needle associated therewith whereby the mouths of said ampoules are caused to enter the inverted cone-shaped funnels of their associated bores to secure said axial alignment, means for downwardly moving said plate to cause said holder to operate as a follower so as to introduce said needles into said ampoules carried thereby, means for arresting the downward follower motion of said holder while continuing the downward displacement of said plate whereby the mouths of said ampoules are spaced from the walls of their cooperating inverted cone-shaped funnels formed by said bores, and means for thereafter injecting cleaning fluid into said compartment for inflow into said needles and outflow therefrom into said ampoules to clean the interior thereof.

35 4. The device as claimed in claim 3, together with a lid disposed on said posts above and in operative engagement with said ampoule holder and spaced from the bottoms of said ampoules and adapted to operatively follow the movement of said ampoule holders, said ampoules being lifted by the pressure of the cleaning fluid injected thereinto to cause the bottoms thereof to engage said lid so as to limit the lifting of said ampoules during the cleaning thereof.

40 5. The device as claimed in claim 3, together with a bowl-shaped perforated lid disposed on said posts above and in operative engagement with said ampoule holder to follow the movement thereof and spaced from the bottoms of said ampoules, said lid having the dual purpose, namely, first, of limiting the upward lifting displacement of said ampoules responsive to the pressure exerted thereon by the cleaning fluid injected thereinto and, second, of receiving cleaning fluid for downward flow therefrom onto said ampoules to clean said ampoules on the outside thereof.
